(57) **CLAIM**

The ornamental design for a window shade, as shown and described.

DESCRIPTION

FIG. 1 is a front side perspective view of a window shade showing our new design, wherein the window shade is partially drawn.

FIG. 2 is a backside perspective view thereof, wherein the shade is partially drawn.

FIG. 3 is a front side perspective view thereof, wherein the window shade is fully drawn;

FIG. 4 is a back side perspective view thereof, wherein the window shade is fully drawn;

FIG. 5 is a view of the front side thereof, wherein the window shade is fully drawn.

FIG. 6 is a view of the backside thereof, wherein the window shade is fully drawn;

FIG. 7 is a top view thereof, wherein the window shade is fully drawn;

FIG. 8 is a bottom view thereof, wherein the window shade is fully drawn;

FIG. 9 is a front side view thereof, wherein the window shade is partially drawn; and,

FIG. 10 is a side elevational view thereof, wherein the window shade is partially drawn.

The broken line showing is for illustrative purposes only and forms no part of the claimed design.
